UNITED STATES PATENT OFFICE.

CHARLES SCHUSTER, OF NEW YORK, N. Y.

DESIGN FOR AN ARTIFICIAL PLANT.

Application filed March 7, 1922. Serial No. 1,070. Term of patent 3½ years.

To all whom it may concern:

Be it known that I, CHARLES SCHUSTER, citizen of the United States, and resident of the city of New York, in the county of Kings and State of New York, have invented a new, original, and ornamental Design for Artificial Plant of which the following is a specification, reference being had to the accompanying drawing, forming part thereof, in which—

The figure is a vertical elevational view of an artificial plant embodying my new design, set in a pot or jardinière (shown in dotted lines).

I claim:

The ornamental design for an artificial plant as shown.

Signed at New York city, March 1st, 1922.

CHARLES SCHUSTER.
